GERMICIDAL PREPARATION

Emil Klarman, Jersey City, N. J., assignor to
Lehn & Fink Products Corporation, a corpora-
tion of Delaware

No Drawing. Application July 28, 1939,
Serial No. 287,113

16 Claims.

(CL 167—25)

The present invention relates to improvements in germicidal or bactericidal preparations having a high bactericidal activity, and more particularly to such preparations containing a germicidal terpineol such as alpha-terpineol or terpineol containing substances such as pine oil, pine oil fractions and the like.

In accordance with the present invention, alpha-terpineol, pine oil, or the terpineol fraction of pine oil, for example, are employed as constituents of mixed germicidal preparations, in which they are found to be capable of decidedly enhancing the germicidal efficiency thereof with respect to such microorganisms as *Streptococcus hemolyticus*, *Ebertella typhi* and *Escherichia coli*.

In preparing germicidal preparations in accordance with the present invention, pine oil, for example, is suitably incorporated in dispersed form in an aqueous vehicle, employing as the dispersing agent a castor oil soap. If desired, other soluble alkali metal soaps of fatty acids of corn oil, linseed oil, olive oil, or other vegetable or animal fatty oils, or mixtures of such soaps may be employed as the dispersing agent. The resulting dispersion is incorporated as a constituent with other germicidal agents, more particularly of a phenolic character, in a composite preparation. In such composite preparations, the pine oil, when present in dispersed form as hereinbefore set forth, definitely enhances the bactericidal effectiveness of the mixture with respect to *Streptococcus hemolyticus*, *Ebertella typhi* and *Escherichia coli*.

In practicing the present invention, it is desirable to mix a fairly concentrated dispersion of alpha-terpineol or pine oil with a solution or similar dispersion of the other germicidal agent or agents. The concentration of the mixed germicidal or bactericidal agents in the preparation may be varied within wide limits. For general use, a concentration of about 0.5% of the total of the germicidal agents has been found to be satisfactory, although more or less concentrated dispersions may, of course, be prepared, say from about 1 to about 10%. For application, the products may be diluted to any desired concentration, say to 1% or to 0.5% and even lower.

In general and in contradistinction to the present discovery, the bactericidal effectiveness of mixtures of germicides is not enhanced or is, in fact, decreased, being in most instances equal to or lower than the calculated additive effect of

accordance with the present invention, pine oil or alpha-terpineol, in combination with other bactericidal agents such as the phenols, particularly the halogenated, and alkylated and halogenated phenols, have the peculiar property of enhancing the bactericidal effectiveness of the mixtures with respect to *Streptococcus hemolyticus*, *Ebertella typhi* and *Escherichia coli*. The enhanced bactericidal effectiveness of the germicidal preparations in accordance with the present invention appears to be selective since with other bacteria, for example, *Staphylococci*, it does not occur.

The following tables are set forth to show the unexpected, enhanced bactericidal effectiveness with respect to *Streptococcus hemolyticus*, *Ebertella typhi* and *Escherichia coli* of mixed germicidal preparations in aqueous dispersions in accordance with the present invention. The tests were carried out at 20° C. using the technique of the Food and Drug Administration Method (Circular No. 198 of the U. S. Department of Agriculture) in the case of *Ebertella typhi*, and one very similar to it, in the case of *Escherichia coli* and of *Streptococcus hemolyticus*.

In the first three tables, *Streptococcus hemolyticus* was used as the test-organism.

TABLE I
Test organism: *Streptococcus hemolyticus*

Substance	Minimum germicidal concentration in 10 minutes	Phenol coefficient
Pine oil	1:10	0.17
Alpha-terpineol	1:10	0.17
p-Chloro-phenol	1:300	5.0
o-Chloro-phenol	1:160	2.7
p-Bromo-phenol	1:375	6.3
o-Bromo-phenol	1:200	3.3
o-Iodo-phenol	1:350	5.8
p-Chloro-m-cresol	1:600	10.0
p-Chloro-symm.m-xylene	1:1200	20.0

Mixtures of equal parts of bactericides (not including pine oil or alpha-terpineol) are in general found to have a bactericidal effectiveness which closely approaches the calculated arithmetical mean of the phenol coefficients of these compounds, as disclosed in my prior Patents No. 1,953,413, dated April 3, 1934; and No. 1,984,646, dated December 18, 1934. When these bactericides are combined in a germicidal prepara-

arithmetical mean of the constituents. Thus, in a series of preparations containing pine oil and another germicidal compound, and alpha-terpineol and another germicidal compound, respectively, in aqueous emulsion as hereinbefore described; that is, with equal proportions of the germicides included in the mixture, the following results were secured:

TABLE II
Test organism: *Streptococcus hemolyticus*

Mixtures of pine oil with—	Minimum germicidal concentration in 10 minutes	Phenol coefficient observed	Phenol coefficient calculated	Increase of efficacy in per cent
p-Chloro-phenol	1:225	3.8	2.6	46
o-Chloro-phenol	1:130	2.2	1.5	47
p-Bromo-phenol	1:275	4.6	3.3	39
o-Bromo-phenol	1:130	2.2	1.8	22 20
o-Iodo-phenol	1:225	3.8	2.8	36
p-Chloro-m-cresol	1:375	6.3	5.1	24
p-Chloro-symm.m-xylenol	1:700	14.0	10.1	39

TABLE III
Test organism: *Streptococcus hemolyticus*

Mixtures of alpha-terpineol with—	Minimum germicidal concentration in 10 minutes	Phenol coefficient observed	Phenol coefficient calculated	Increase of efficacy in percent
p-Chloro-phenol	1:225	3.8	2.6	46
o-Chloro-phenol	1:140	2.3	1.5	53
p-Bromo-phenol	1:250	4.2	3.3	27
o-Bromo-phenol	1:150	2.5	1.8	39
o-Iodo-phenol	1:225	3.8	2.8	36
p-Chloro-m-cresol	1:400	6.7	5.1	31
p-Chloro-symm.m-xylenol	1:800	13.3	10.1	32

It is apparent from the foregoing tables that in the case of *Streptococcus hemolyticus*, the germicidal preparations in accordance with the present invention have an increased bactericidal effectiveness over the phenol coefficient figures calculated on a basis of the expected additive effects of the component germicides of the mixture.

The following tables IV, V and VI refer to tests with *Ebertella typhi*.

TABLE IV
Test organism: *Ebertella typhi*

Substance	Minimum germicidal concentration in 10 minutes	Phenol coefficient
Pine oil	1:350	4.4
Alpha-terpineol	1:325	4.1
p-Chloro-phenol	1:500	6.3
p-Bromo-phenol	1:700	8.8
p-Chloro-m-cresol	1:1200	15.0
p-Chloro-symm.m-xylenol	1:2000	25.0

TABLE V
Test organism: *Ebertella typhi*

Mixtures of pine oil with—	Minimum germicidal concentration in 10 minutes	Phenol coefficient observed	Phenol coefficient calculated	Increase of efficacy in percent
p-Chloro-phenol	1:500	6.3	5.4	17
p-Bromo-phenol	1:700	8.8	6.6	33
p-Chloro-m-cresol	1:1000	12.5	9.7	29
p-Chloro-symm.m-xylenol	1:1600	20.0	14.7	36

TABLE VI
Test organism: *Ebertella typhi*

Mixtures of alpha-terpineol with—	Minimum germicidal concentration in 10 minutes	Phenol coefficient observed	Phenol coefficient calculated	Increase of efficacy in percent
p-Chloro-phenol	1:500	6.3	5.2	21
p-Bromo-phenol	1:700	8.8	6.5	35
p-Chloro-m-cresol	1:800	10.6	9.6	10
p-Chloro-symm.m-xylenol	1:1500	18.8	14.6	29

The increase of bactericidal efficacy, in accordance with the present invention is distinctly in evidence.

Tables VII, VIII and IX give the results of experiments with *Escherichia coli* as the test organism.

TABLE VII
Test organism: *Escherichia coli*

Substance	Minimum germicidal concentration in 10 minutes	Phenol coefficient
Pine oil	1:500	7.1
Alpha-terpineol	1:450	6.4
p-Chloro-phenol	1:500	7.1
p-Bromo-phenol	1:800	11.4
p-Chloro-m-cresol	1:1200	17.1
p-Chloro-symm.m-xylenol	1:2000	28.6

TABLE VIII
Test organism: *Escherichia coli*

Mixtures of pine oil with—	Minimum germicidal concentration in 10 minutes	Phenol coefficient observed	Phenol coefficient calculated	Increase of efficacy in percent
p-Chloro-phenol	1:650	8.1	7.1	14
p-Bromo-phenol	1:800	10.0	9.3	8
p-Chloro-m-cresol	1:1000	14.3	12.1	18
p-Chloro-symm.m-xylenol	1:1600	22.9	17.9	28

TABLE IX
Test organism: *Escherichia coli*

Mixtures of alpha-terpineol with—	Minimum germicidal concentration in 10 minutes	Phenol coefficient observed	Phenol coefficient calculated	Increase of efficacy in percent
p-Chloro-phenol	1:600	8.6	6.8	26
p-Bromo-phenol	1:700	10.0	8.9	12
p-Chloro-m-cresol	1:1000	14.3	11.8	21
p-Chloro-symm.m-xylenol	1:1600	22.9	17.5	31

As in the case of *Streptococcus hemolyticus* and of *Ebertella typhi*, there is a substantial enhancement of bactericidal activity with respect to *Escherichia coli* of the mixtures as compared with the calculated additive figures of the components.

It is readily apparent that various flavoring or perfuming constituents, soluble substances for modifying surface tension, bland oils or the like may be introduced into the aqueous vehicle of the germicidal preparation made in accordance with the present invention in producing commercial products.

The tests set forth in the above tables were made on diluted stock solutions. In all but one instance, the stock solutions consisted of the active germicidal material or materials 50%, anhydrous castor oil soap 40%, and water

(+ glycerine from saponification of the castor oil) 10%. In the one instance, viz., that of p-chloro-m-symm.xyleneol, a modified formula was used because of lower solubility of the phenol derivative (p-chloro-m-symm.xyleneol 25%, castor oil soap 20%, water+glycerine 5%, alcohol 50%).

Although the present invention has been described in connection with details of specific examples embodying the same, it is not intended that it shall be regarded as limited thereto, except in so far as included in the accompanying claims.

I claim:

1. A germicidal preparation having an enhanced bactericidal effectiveness comprising an aqueous dispersion of a germicidal substance of the class consisting of alpha-terpineol and pine oil and a halogenated phenolic body having germicidal properties.

2. A germicidal preparation having an enhanced bactericidal effectiveness comprising an aqueous dispersion of a germicidal substance of the class consisting of alpha-terpineol and pine oil and an alkylated halogenated phenolic body having germicidal properties.

3. A germicidal preparation having an enhanced bactericidal effectiveness, comprising an aqueous dispersion of pine oil and a halogenated phenol.

4. A germicidal preparation having an enhanced bactericidal effectiveness comprising an aqueous dispersion of pine oil and a chloro-phenol.

5. A germicidal preparation having an enhanced bactericidal effectiveness comprising an aqueous dispersion of pine oil and a chloro-cresol.

6. A germicidal preparation having an enhanced bactericidal effectiveness comprising an aqueous dispersion of pine oil and a chloro-xyleneol.

7. A germicidal preparation having an enhanced bactericidal effectiveness comprising an aqueous dispersion of alpha-terpineol and a halogenated phenol.

8. A germicidal preparation having an enhanced bactericidal effectiveness comprising an aqueous dispersion of a terpineol and a halogenated phenol.

9. A germicidal preparation having an enhanced bactericidal effectiveness comprising an aqueous dispersion of alpha-terpineol and a chloro-phenol.

10. A germicidal preparation having an enhanced bactericidal effectiveness comprising an aqueous dispersion of alpha-terpineol and a chloro-cresol.

11. A germicidal preparation having an enhanced bactericidal effectiveness comprising an aqueous dispersion of alpha-terpineol and a chloro-xyleneol.

12. A germicidal preparation having an enhanced bactericidal effectiveness comprising an aqueous dispersion of a germicidal substance of the class consisting of alpha-terpineol and pine oil and a monohalogenated phenolic compound having germicidal properties.

13. A germicidal preparation having an enhanced bactericidal effectiveness comprising an aqueous dispersion of a germicidal substance of the class consisting of alpha-terpineol and pine oil and a phenolic compound of the class consisting of the ortho- and para-monohalogenated, mononuclear phenols.

14. A germicidal preparation having an enhanced bactericidal effectiveness comprising an aqueous dispersion of a germicidal substance of the class consisting of alpha-terpineol and pine oil and a phenolic compound of the class consisting of the ortho- and para-monohalogenated, mononuclear, alkyl substituted phenols.

15. A germicidal preparation having an enhanced bactericidal effectiveness comprising an aqueous dispersion of pine oil and a monochloro, mononuclear, monohydric phenol.

16. A germicidal preparation having an enhanced bactericidal effectiveness comprising an aqueous dispersion of alpha-terpineol and a monochloro, mononuclear, monohydric phenol.

EMIL KLARMANN.
